UNITED STATES PATENT OFFICE

168,610

MOTION-PICTURE CAMERA

Walter H. Bach, Los Angeles, and Robert L. George, Torrance, Calif., assignors to Berndt-Bach, Incorporated, Los Angeles, Calif., a corporation of California

Application July 28, 1952, Serial No. 20,791

Term of patent 14 years

(Cl. D61—1)

To all whom it may concern:

Be it known that we, Walter H. Bach and Robert L. George, both citizens of the United States of America, residing at Los Angeles and Torrance, respectively, in the county of Los Angeles, State of California, have invented a new, original, and ornamental Design for a Motion-Picture Camera, of which the following is a specification, reference being had to the accompanying drawing, forming a part hereof.

Figure 1 is a left-front oblique perspective view of a motion-picture camera showing our new design;

Figure 2 is a right side elevational view of the camera of Figure 1;

Figure 3 is a right-rear oblique, enlarged perspective view thereof; and

Figure 4 is a top plan view thereof.

We claim:

The ornamental design for a motion-picture camera, substantially as shown.

WALTER H. BACH.
ROBERT L. GEORGE.
